UNITED STATES PATENT OFFICE.

LUTHER E. HIGBY, OF BRATTLEBOROUGH, VERMONT.

SEWING-MACHINE.

SPECIFICATION forming part of Letters Patent No. 256,141, dated April 11, 1882.

Application filed April 16, 1881. (No model.)

To all whom it may concern:

Be it known that I, LUTHER E. HIGBY, a resident of Brattleborough, in the county of Windham and State of Vermont, have invented 5 certain new and useful Improvements in Sewing-Machines; and I do hereby declare the following to be a full, clear, and exact description of the invention, such as will enable others skilled in the art to which it appertains to make and 10 use the same, reference being had to the accompanying drawings, and to letters of reference marked thereon, which form a part of this specification.

The object of this invention is to facilitate 15 the action of sewing-machines, to reduce the cost of construction by doing away with certain intermediate parts, to render their operation noiseless, and to simplify and otherwise improve said machines.

20 The invention consists in the construction, combination, and arrangement of parts, as will be hereinafter fully and definitely embodied in the claims.

Referring to the accompanying drawings, 25 (comprised in two sheets,) in which similar letters of reference indicate like parts in each of the several figures, Figure 1 is a sectional elevation of a portion of a sewing-machine embodying and illustrating my improvements; 30 Fig. 2, a horizontal section taken through Fig. 1 in the direction indicated by the arrow; and Fig. 3 is an enlarged side elevation of the mechanism, more clearly illustrating the same.

In carrying out my invention I construct 35 upon the horizontal driving-shaft D, which operates the sewing mechanism, an eccentric, C, which actuates a connecting-rod, G, which in turn operates the feed-shaft L by means of a crank, K, having the same stroke as the eccentric C, as will be manifest. Said connecting- 40 rod is held in engagement with eccentric C by eccentric-strap H, which encircles said eccentric C, as indicated in Fig. 1. The feed-shaft L operates the feed-bar N by means of a cam, M, which causes the said bar and feed there- 45 with connected to move both vertically and laterally.

The connecting-rod G has a supplemental adjustable rod, S, arranged therewith, as shown, 50 to aid in its adjustment upon the eccentric and crank. Said rod G also actuates the shuttle-

lever B by means of a shuttle-lever shaft, A, as will be hereinafter set forth.

The shaft D carries a hanging socket, I, and the table or bed-plate W carries a co-operating socketed bracket, J, which parts, taken together, form bearings for the said shuttle-lever shaft A. Upon the latter are formed arms F, through which the connecting-rod G passes, and near the lower extremity of said shaft is 60 rigidly secured the shuttle-lever B.

As will be clearly understood, the eccentric C, as the shaft D revolves, imparts to the connecting-rod G not only a vertical motion, but a lateral, which causes the shaft A to move 65 reciprocally in the sockets or bearings I J, thereby imparting to the lever B therewith rigidly connected the required reciprocating horizontal motion, as indicated more particularly in Fig. 2.

The shuttle-lever B is firmly secured to shuttle-lever shaft A in a direct line with the lower arm, F, a portion of which arm passes through shuttle-lever B, so that each steadies the other, and the connecting-rod G, sliding in the arms 70 F F, relieves the shuttle-lever shaft of considerable strain and secures an easy movement of the parts.

The advantages of my improved mechanism are several, to wit: A direct action is imparted 80 to the shuttle-lever B and feed-bar M. The device is simple, compact, easily constructed, silent when in motion, and does away with intermediate levers, studs, and ball-joints, all of which give more or less backlash or lost motion.

By means of the box I, which hangs from the driving-shaft D, as indicated in Figs. 1 and 4, and which adjusts itself to the shuttle-lever shaft when the extremity of the same is inserted in the socketed bearing therein, much 90 time, skill, and labor are saved in constructing the machine.

In machines heretofore in use, and of which we are aware, having a shuttle-lever shaft there-in similarly disposed in relation to a connecting-rod, G, and having rigid bearings for the extremities thereof, much care and skill are required to prevent the several bearings from binding, and thus superinducing unnecessary friction; but by my device the box I, by turning or allowing of being turned upon the shaft 95 100

D, adjusts itself in proper and easy bearing relation to the shuttle-lever shaft without the exercise of the care and skill above mentioned.

It will be observed, also, that the shaft A, rod G, and connections can be tested before being placed in the arm of the machine, and when satisfactorily constructed to operate can be placed in the machine-arm without further testing.

Having thus described my invention, what I claim, and wish to secure by Letters Patent, is—

1. In a sewing-machine, the combination, with the shuttle-lever B, rigidly secured to the shuttle-lever shaft, of said shuttle-lever shaft actuated to a lateral reciprocating pivotal action in the bearings I J by the connecting-rod G, and having arms F projecting therefrom, the lower arm passing through and working with said shuttle-lever, all said parts being constructed, arranged, and operating substantially as set forth and shown, for the purposes specified.

2. The combination, in a sewing-machine, with the driving-shaft D, of the rod G, connecting the eccentric G and crank upon the extremity of the feed-shaft L, and passing through arms projecting from a shuttle-lever shaft, the said shuttle-lever shaft working in

the bearing I, hanging from the driving-shaft, 30 and bearing J upon the bed-plate, and having the lower arm, F, passing through the shuttle-lever, the shuttle-lever secured rigidly to the shuttle-lever shaft and actuated thereby, and the feed-shaft, all arranged and operating substantially as and for the purposes set forth and shown.

3. In a sewing-machine, the combination, with the driving-shaft D and shuttle-lever shaft A, having a lateral reciprocating pivotal action, of the bearing J, receiving the lower extremity of said shuttle-lever shaft, and the box I, suspended from said driving-shaft and supported thereby, and having a socketed bearing directly beneath said driving-shaft 40 adapted to receive and receiving the upper extremity of said shuttle-lever shaft, the whole being arranged and operating substantially as and for the purposes herein set forth and shown.

In testimony that I claim the foregoing I have hereunto set my hand this 7th day of April, 1881.

LUTHER E. HIGBY.
